ATTORNEY.

UNITED STATES PATENT OFFICE

BRICE M. CAMPBELL, OF DALLAS, TEXAS

GARMENT MEASURING DEVICE

Application filed March 24, 1930. Serial No. 438,303.

This invention relates to garment measuring devices and it has particular reference to a scale for wearing apparel and the principal object of the invention resides in the provision of a device of the character specified of particular benefit to the garment cleaning, dyeing and pressing profession by which a garment, when received by an establishment for cleaning can be measured as to length and width and as to dimensions of other portions thereof, such as sleeves, collars and the like, before said garment has been immersed in cleansing solution.

Another object of the invention is to provide through the medium of graduated markings, by which the garment, after cleaning can be again measured for shrinkage, which measurements before and after cleaning are tabulated and compared, and should shrinkage occur, as determined by the measuring device, the cleaner is enabled to return the garment to its original size through a steaming process.

Broadly, the invention comprehends through the medium of the invention herein defined, the provision of a measuring device which will not only assist the cleaner in his profession but will likewise enable him to satisfy his patrons in that he is enabled to correct shrinkage in the garment before delivery to the patron, which shrinkage can ordinarily be overcome by a steaming process, possibly unknown to the patron yet may be accomplished by the cleaner who has the prior knowledge of the original size of the garment, through the medium of the scale embodied in the present invention.

With the foregoing objects as paramount, the invention has particular reference to its salient features of arrangement of parts, to become manifest as the description proceeds, taken in connection with the accompanying drawing, wherein:

Figure 1 shows the preferred embodiment of the invention, as applied to a vertically disposed and portable panel.

Figure 2 is a side elevational view and,

Figure 3 is a fragmentary view showing the graduated markings on the various scales.

In the garment cleaning, dyeing and press-

ing art, great responsibility rests upon the cleaner who receives expensive wearing apparel and it frequently occurs, through no fault of the cleaners that a garment, when subjected to the action of the cleaning solution shrinks below the original size. Should a garment be delivered to a patron in this condition, dissatisfaction occurs and the cleaner suffers the loss of the patron's business and is sometimes required to pay for the garment. Heretofore, there has been no medium through which the cleaner could obtain measurements of the garments except by means of a tape measure or similar device, which does not conveniently show the dimensions. A garment which has been shrunk by contact with a cleaning solution may be returned to its normal size through a steaming process; but without any definite means of obtaining measurements, the cleaner is unable to return the garment to its original size.

The present invention therefore is effective in protecting the cleaner against conditions arising as set out in the foregoing, that is to say, he is enabled to obtain measurements before and after cleaning of the garment, which operation may be made without the knowledge of the patron. However, the fact that a cleaner advertises his use of a garment scale, such as disclosed herein, would be an inducement to particular persons to deal with the cleaner who has adopted means by which to correct shrinkage.

Accordingly, the present invention, in its preferred form is comprised of a panel 1, vertically disposed upon legs 2 and is situated within a frame 3. For convenience in moving the panel about, the panel is mounted upon casters 4.

Adjacent the top of the panel there is provided a hook 5 upon which is suspended a garment hanger 6.

It is preferred that the several measuring devices, to which reference will be later made, be drawn or printed upon paper or other suitable material and applied to the panel 1, in the manner shown in Figure 1. Such construction is economical, yet does not detract in any way from the usefulness of the device.

Preferably, there are provided three spaced columns of graduated markings, which columns are designated as *a*, *b* and *c*, as shown in Figure 1. A series of horizontal scales *d* 5 intercross the vertical columns *a*, *b* and *c*. Situated at an angle relative to the three vertical columns are scales *e*, while on either side of the vertical columns there are situated oblique scales *f*. These latter scales are inter- 10 crossed by short scales *g*. Immediately below these scales *g* are similar scales *h*. At the lower left of the scale assembly shown in Figure 1 there is situated an adjacent oblique scale *i*. 15 In measuring a garment, which is shown in dotted lines on the measuring device shown in Figure 1, the garment is hung upon the hanger 6 and the columns *a*, *b* and *c* are used to measure the length of a garment while 20 scales *d* indicate width of the skirt, waist and waist line as well as the shoulders, in the case of ladies wearing apparel. The scales *e* at the top of the assembly are effective in measuring the distance between the collar and the 25 shoulder seam, while the scales *f* are used to measure the length of the sleeves of the garment. The scales *g* and *h* are employed for obtaining the measurements of the width of the sleeves and cuffs. The obliquely arranged 30 scale *i* at the left of the assembly in Figure 1 is used in the case of a full skirt.

When a garment enters the cleaning establishment to be cleaned, the cleaner first suspends the garment in the manner shown in 35 Figures 1 and 2, and through the medium of the characters capitalized on the drawing, such for example as "J" and "L" at the tops of columns *a* and *c*, he is enabled to tabulate the correct measurement of a garment by reference to corresponding characters which may 40 be written down along with the measurements obtained from the various scales above referred to. This affords the cleaner with an accurate measurement of the garment, a copy 45 of which measurements is presented to the owner of the garment. After the garment is cleaned, it is again suspended on the measuring device as shown and measurements are again obtained, and should there be a deficiency, the cleaner is enabled to subject the garment to a steaming process to return the same to its original size, which is determined 50 by again placing the garment on the scales.

It is understood that the present invention 55 is not limited to the specific manner of mounting since the scale assembly may be laid out in the form shown on the flat or inclined top of a table of such size as to accommodate the garment. The particular advantage of the 60 present mounting is that the measuring device occupies but a minimum of space but the foregoing is mentioned since equal effectiveness is obtainable by laying out the scale on the cutting table.

65 Manifestly, the construction shown is cap-

able of considerable modification and such modification as is considered within the scope and meaning of the appended claim is also considered within the spirit and intent of the invention.

70

What is claimed is:

In a garment measuring device, the combination comprising a vertical rectangular frame and a chart mounted therein having a garment hanger suspending means affixed 75 near its top midway between its sides, said chart further having represented thereon a series of vertical, calibrated lines intercrossed by a series of spaced, calibrated lines and another series of calibrated lines arranged at a 80 variety of angles relative to said first lines, all of said lines being positioned to effect measurement of the parts of a garment suspended over said chart.

85

In testimony whereof I affix my signature

BRICE M. CAMPBELL.
